UNITED STATES PATENT OFFICE.

HERMAN C. PRIEBE, OF BLUE ISLAND, ILLINOIS.

ROCKER-BOTTOM CAR.

No. 876,587.

Specification of Letters Patent.

Patented Jan. 14, 1908.

Application filed March 30, 1907. Serial No. 365,458.

To all whom it may concern:

Be it known that I, HERMAN C. PRIEBE, a citizen of the United States, residing at Blue Island, Cook county, Illinois, have invented 5 certain new and useful Improvements in Rocker-Bottom Cars, of which the following, taken in connection with the drawings, is a description.

My invention has for its object the production of rocker bottom doors for dump cars, the doors being so arranged that the load may be dropped directly beneath the car, or at the side thereof as desired. Each 10 of the doors or sections are constructed so that they swing or tilt from closed to open position, and are provided with a lock upon the outside thereof, and when unlocked the weight contained in the car is sufficient to rock the door on its bearings.

20 In the accompanying drawings I have illustrated the preferred form of my invention, although it is obvious that the details thereof might be modified without departing from the spirit of my invention, and I wish to be 25 understood as contemplating any such changes in construction.

Figure 1 is a side elevation of a car partly in section illustrating my invention applied thereto. Fig. 2 is an enlarged sectional view 30 taken on line 2—2 of Fig. 1; Fig. 3 is an enlarged view of one of the doors in opened position; Fig. 4 is a modified form of construction illustrating the doors swinging on a hinge secured to the bottom of the floor; Fig. 35 5 is another modification illustrating the doors opening at the outer sides of the car to dump the load. Fig. 6 is a detail taken on line 6—6 of Fig. 5.

In carrying out my invention A represents 40 the side of a hopper bottom car, a section of the side being broken away to expose one of the doors which is in opened position. As the car, the frame, the bolsters, etc. form no part of this invention I will not give a detailed description thereof.

Extending longitudinally of the car through the center thereof is an inclined partition a, and extending transversely of said car is another inclined partition a', these partitions 50 forming with the inclined ends b', b' of the car, a plurality of hoppers through each of which a portion of the load is dropped through the opened door or section. Guards a" extend downwardly from each of these inclines 55 to a point meeting the inner edge of the car door when in closed position.

In the form of construction shown in Figs. 1 and 2 I have shown two doors upon each side of the center sill of the car. As both of these doors are constructed and operated alike 60 I will describe but one of them.

Extending transversely of the car and secured to the underframe thereof are the rocker shafts B, B, upon which the door sections B', B', swing. The door sections B', 65 B', are carried upon the skeleton frames b, which frames are mounted upon the rocker shafts B which form the axes upon which the doors or sections are rocked when opened. The frames b fit over the top of the rocker 70 shaft B and have extending therethrough and beneath the shafts U-bolts b² (shown more clearly in Figs. 5 and 6). Extending parallel with each door section is a rod C having formed therein the cranks c, c' each 75 of which passes through one end of a link D', D', and which are adapted to be raised and lowered as the door sections are opened and closed. Levers C', C² are secured to these rods at the outer ends thereof, by means of 80 which the rods are released and turned to open the door. The links D, D' extend from the cranks c, c' to the open end of the door or section and are pivotally secured to a projection or flange d extending from the frame b. 85 A similar projection d² extends beyond the center of the door section and when the door is in closed position said projection extends through a link d³ which is secured to the side of the car, and a hook or pin d⁴ is passed 90 therethrough to prevent said door from opening in case of accident or otherwise.

In Fig. 5 of the drawings I have shown a transverse section illustrating the doors opening from the sides of the car, but otherwise employing the same construction as that described above.

In Fig. 4 I have shown a modified form of construction in which the door sections are hinged to the floor at E and open downwardly as shown.

The operation is as follows: When the car is ready for unloading the hook d⁴ is displaced from the eye d² and the operating levers C', C² turned to release the rods C 105 when the weight of the load in the car will throw the floor sections off balance and rock them to opened position as shown more particularly in Fig. 3. After the car is empty the levers are raised, carrying the cranks c, c' 110 and the links D, D' with them until the door sections are closed, the link d³ fits over the

eye d^2 and the hook d^4 is passed therethrough, when the car is ready to be unloaded.

I claim:—

1. The combination of the car body having a hopper bottom therein, a plurality of doors extending transversely across the bottom of said car, rocker shafts upon which said doors are mounted, and means for rocking or tilting said doors to open position.
2. A car having a hopper bottom therein, a plurality of door sections extending transversely of said car and opening downwardly at each side of the hopper bottom, rocker shafts extending transversely of said car and approximately mediate of the width of the door sections, and means for rocking or tilting the aforesaid door sections on said shafts.
3. The combination of a hopper bottom car, rocker shafts extending transversely of said car, a plurality of door sections mounted upon frames adapted to tilt or rock on said shafts approximately mediate of the width of said door sections, U-bolts extending around said shaft and secured to the door frame, and supports for said door sections when in opened position.
4. The combination of a hopper bottom

car, rocker shafts extending transversely of said car, a plurality of door sections mounted upon and adapted to be tilted on said shafts approximately mediate of the width of said door sections, links secured to the outer edges of said door sections, a rod extending parallel with said doors to which said links are loosely secured and means for actuating said rod to open or close said door sections.

5. The combination of a hopper bottom car, a plurality of door sections opening from the bottom of said car, rocker shafts upon which said door sections are mounted approximately mediate of the width thereof, rods journaled in bearings secured to the car, links connected to said rods and to the outer edges of the door sections, and means for operating said rods to raise and lower the door sections.

In testimony whereof I have signed this specification in the presence of two subscribing witnesses.

HERMAN C. PRIEBE
